UNITED STATES PATENT OFFICE.

ERNEST ORIN LINTON, OF HAMMOND, INDIANA, ASSIGNOR TO CALUMET ENGINEERING CORPORATION, OF EAST CHICAGO, INDIANA, A CORPORATION OF INDIANA.

FUEL-OIL BURNER.

Application filed March 19, 1923. Serial No. 626,150.

This invention relates to liquid fuel or fuel oil burners particularly designed and adapted for the production of very high temperatures wherever required such as for instance in steel, brass and other metal-working furnaces, reheating furnaces and the like. The invention relates further to a novel process of burning liquid fuels such as heavy hydrocarbon or petroleum oils, tar and the like.

One form of burner embodying my invention is illustrated in the accompanying drawings and the invention is described in connection therewith, it being understood however that the invention is not limited to the specific details described and illustrated.

On the drawings—

Fig. 1 is a plan view of a complete burner with parts broken away in cooperative relation with a tuyère shown in section taken on line 1—1, Fig. 2, and a broken section of the furnace wall.

Fig. 2 is an elevation of the complete burner in cooperative relation with the tuyère and a broken section of the furnace wall.

Fig. 3 is a vertical cross-section of the burner on the line 3—3 of Fig. 2 looking in the direction of the arrows.

Fig. 4 is a vertical cross-section on the line 4—4 of Fig. 2 looking in the direction of the arrows.

Fig. 5 is a section through the muffler showing also the air mixing tube of the burner.

Fig. 6 is a sectional view of the steam and oil connections.

Fig. 7 is a broken section of the burner at the nozzle end of the oil lead-in pipe on the line 7—7 of Fig. 8, the oil pipe being shown in elevation, and

Fig. 8 is a vertical section on the line 8—8 of Figs. 1 and 7 looking in the direction of the arrows.

The burner is designed to form by its own operation a highly heated combustible gas mixture from steam and fuel oil. To this end fuel oil and steam are separately supplied to conduits forming a part of the burner in which both the steam and oil are highly heated by heat from the burner flame and the resulting oil and steam are mixed and conducted through a single conduit forming a part of the burner in which the mixture is further heated by heat derived from the burner flame. The result is a

highly heated special gas mixture having a high calorific value and excellent burning properties which is delivered admixed with air to the burner flame.

The burner comprises a valve-controlled oil supply pipe 1 suitably connected to the oil lead-in pipe 2 which lies within and concentric with the steam lead-in pipe 3 supplied with steam through the valved steam supply pipe 4. At about the source of the burner flame the steam lead-in pipe 3 is connected with the steam superheating pipe 5. The oil lead-in pipe 2 extends forwardly in the steam superheating pipe 5 to a point adjacent the forward end thereof terminating therein in a nozzle or jet 6. The pipe 2 is supported concentrically within the pipe 5 by one or more spiders 7. As is illustrated the forward end of the pipe 2 is screw threaded into a central opening in the spider 7. The steam superheating pipe 5 is connected through the 180° return bend 8 to the oil vaporizing and mixing pipe 9, said pipe 9 extending backwardly parallel to the pipe 5 to a point adjacent to the source of the burner flame where it connects with the mixture feed pipe 10 leading to the burner jet or nozzle 11. The steam superheating pipe 5 and the oil vaporizing and mixing pipe 9 are of relatively large size as compared with the oil and steam supply pipes 1 and 4 and the mixture feed pipe 10. This is to provide for a sufficiently slow passage of the steam through the pipe 5 so that it will be superheated to the desired extent, and for a sufficiently slow passage of the oil vapor and steam mixture through the pipe 9 so that the desired vaporizing and cracking of the oil and reaction between the oil and steam will take place.

In order to provide for the cleaning of the pipes 9 and 10 the pipe 10 is connected to the burner nozzle 11 through a T 12, having the plug 13 in alignment with the pipes 9 and 10. In like manner provision is made for the cleaning of the pipes 3 and 5 and for the removal and replacement of the pipe 2 by means of the reducing plug 14 through which the oil supply pipe 1 and the oil lead-in pipe 2 are connected. The burner nozzle 11 discharges into the air mixing tube 15 which lies between the pipes 5 and 9 and is open at both ends, the front end being the source of the flame, while the rear end is connected with the air muffler 16. Surround-

ing the air mixing tube 15 and concentric therewith about the middle thereof is the supporting and auxiliary air inlet pipe 17. The pipe 17 is held in place on the tube 15 5 as illustrated see (Figs. 1, 2, and 3) by set screws 18.

The structure described above constitutes the burner proper, the whole being designed as a unit, although as is apparent the several 10 parts are detachable. The burner may be supported in any suitable manner, but is particularly designed as heretofore stated for use in furnaces, in which case it should be mounted in a tuyère. The tuyère may be 15 simply an opening in the furnace wall and the burner supported therein in any suitable manner. For best operation however the size of the tuyère opening, relative to the size of the burner, should be about as illustrated. It is moreover desirable to provide 20 for the ready removal of the burner from the tuyère for cleaning, replacement etc. I have therefore designed a tuyère suitable for use with the burner. The tuyère comprises 25 a tube 19 of slightly greater internal diameter than the sum of the external diameters of the three pipes 5, 9 and 15 and adapted to fit snugly in an opening in the furnace wall 20. The tuyère tube 19 has a shoulder 30 21 adapted to bear against the inner face of the furnace wall 20 and an arm 22 which carries the set screws 23 adapted to be tightened against the outer face of the furnace wall. Within the tuyère tube 19 (see Figs. 35 3 and 4) are oppositely disposed pairs of shoulders 24 forming channels 25 for receiving the pipes 5 and 9 of the burner. The end of the tuyère tube 19 which projects outside of the furnace wall 20 carries set screws 40 26 adapted to bear against the auxiliary air inlet pipe 17. The burner is thus supported and positioned within the tuyère by the shoulders 24 and the set screws 26.

The burner is operated as follows:

45 Fuel oil, particularly the heavier grades, or tar preheated to a freely fluent condition is supplied to the pipe 1 and steam, preferably superheated to avoid condensation, is supplied to the pipe 4. The steam and oil 50 should be supplied under pressure not only to provide the desired rate of flow but also to provide for the desired atomizing action at the jet 6 of the oil lead-in pipe 2. Suitable pressures are from 100 to 150 pounds 55 per square inch for the steam and a lower pressure for the oil, say 80 pounds per square inch. The relative rate of supply of oil and steam preferably is about 5 parts by weight of steam to one part by weight of oil, although 60 these proportions may be varied as desired within a wide range. Within the pipe 5 the steam is highly superheated by the flame of the burner, reaching a temperature of say 1500° to 1800° F. or higher and 65 the oil in the pipe 2 is also heated to its

vaporizing and cracking temperature. At the end of the pipe 2 the oil discharges into the superheated steam in the form of a spray or vapor and the mixture passes on through the return bend 8 and the oil vaporizing and mixing pipe 9 in which it is further heated. As a result of the heating of the mixture of steam and oil vapor to a high temperature both the oil and the steam apparently decompose or crack and interact 70 with each other, giving a highly heated special combustible gas mixture containing a relatively high proportion of unsaturated hydrocarbons including ethylene, which when mixed with air or oxygen and burned 75 gives a clean flame having a temperature in the neighborhood of 4000 to 4300° F. This gas mixture formed in the pipe 9 passes by way of the pipe 10 to the burner jet 11 where it is delivered into the air mixing 80 tube 15. The force of the stream of fuel issuing through the jet 11 into the mixing tube 15 draws air into tube 15 through the muffler 16. The muffler 16 eliminates to a great degree the loud roar that ordinarily 85 accompanies the operation of burners operating under a high pressure blast. In the tube 15 the fuel and air mix together and issue through the end of tube 15 where they burn, giving a very hot non-luminous flame. 90 Additional air is supplied to the flame through the supporting and auxiliary air inlet pipe 17 and still a further quantity of air is supplied to the flame through the tuyère 95 tube 19. The aspirating action of the gas discharged from the end of the tube 15 draws the auxiliary air through the pipe 17 and the tuyère 19 referred to. This auxiliary supply of air greatly assists the complete combustion of the fuel, thus increasing 100 the quantity of heat derived from the fuel, and also by completely burning the fuel decreases the quantity of smoke or soot which would otherwise be produced by the flame.

105 It will be noted that one feature of the operation of my burner is the preheating of the fuel by means of heat derived from the flame of the burner itself. Another important feature of the operation of the burner is the preparation of a highly heated special gaseous fuel by the heat treatment of the steam and hydrocarbon fuel supplied to the burner. Due to the heat treatment and gasification of the fuel intimate admixing of the fuel with air and quick and complete combustion of the fuel with the production of a very high temperature and a clean flame are made possible.

I claim:

125 1. A fuel oil burner comprising a U-shaped conduit, means for supplying steam to one end of said U-shaped conduit, an oil conduit extending within one arm of said U-shaped conduit and discharging adjacent the return bend of said U-shaped conduit,

and a burner jet communicating with the other end of said U-shaped conduit and lying between the two arms thereof.

2. A fuel oil burner comprising a steam superheating pipe, an oil lead-in pipe within said steam superheating pipe, an oil vaporizing and mixing pipe communicating with said steam superheating pipe, a mixture feed pipe communicating with said oil vaporizing and mixing pipe, and an air mixing tube communicating with said mixture feed pipe.

3. A fuel oil burner comprising a steam superheating conduit, an oil lead-in conduit

extending longitudinally within said steam superheating conduit, an oil vaporizing and mixing conduit communicating with said steam superheating conduit, said conduits lying in the path of the flame of the burner, a mixture feed pipe, an air mixing tube positioned to receive the fuel delivered by said mixture feed pipe, and an auxiliary air inlet pipe surrounding and spaced from said air mixing tube.

In testimony whereof, I affix my signature.

ERNEST ORIN LINTON.
